UNITED STATES PATENT OFFICE.

VICTOR KOBLER, OF RORSCHACH, SWITZERLAND, ASSIGNOR TO THE FIRM OF ADOLPH SAURER, OF ARBON, SWITZERLAND.

JACQUARD APPARATUS FOR EMBROIDERING-MACHINES.

1,059,880.

Specification of Letters Patent. Patented Apr. 22, 1913.

Application filed March 6, 1911. Serial No. 612,633.

To all whom it may concern:

Be it known that I, VICTOR KOBLER, a citizen of the Republic of Switzerland, residing at Promenadenstrasse 92, Rorschach, Switzerland, have invented new and useful Improvements in Jacquard Apparatus for Embroidering-Machines; and I do hereby declare the following to be a full, clear, and exact description of the invention, such as will enable others skilled in the art to which it appertains to make and use the same.

The jacquard apparatus constructed according to this invention comprises blades which are adapted to be separately dis- placed from the jacquard card and to be combined in groups.

With the device herein described it is possible to have a large number of different combinations of the relative position of the blades of different groups, and only a small jacquard card is necessary. For this purpose means controlling the stroke of the frame are provided for each group and arranged transversely to the blade, the arrangement being such, that if all blades of a group are disengaged from the jacquard card, all controlling means belonging to this group are arrested, while if one or several blades of a group are displaced, according to the resulting relative position of the blades one of said controlling means is released.

Reference is to be had to the accompanying drawings in which:

Figure 1 is a side elevation of an apparatus embodying my invention connected to an embroidering machine. Fig. 2 is a vertical section of the apparatus, on line 2—2 of Fig. 4. Fig. 3 is a section at right angles to Fig. 2, seen from the left. Fig. 4 is a plan view of the apparatus, parts being broken away. Fig. 5 is a diagrammatic view showing the blades in different positions.

Referring to Fig. 1, 5 designates the frame of the apparatus forming the subject matter of this invention, 67 the pantograph and 68 the embroidering frame.

1 designates the main shaft to which motion is imparted from a suitable source of power. On this shaft are fixed two cams 2, on which bear rollers 3, carried on levers 4, which are pivoted at 6 on the machine frame 5. The free ends of the levers 4 are pivoted 55 to supporting arms 7, the upper ends of

which are in the shape of frames 8 and are connected by a rod 9, and stays 10.

The frames 8 carry the pushing blades 11 which are divided into four groups A, B, C, D each of which comprises five blades 60 a, b, c, d, f. Each of the blades a, b, c, d, has a broad recess at the bottom so that only a portion 12 of each blade retains the breadth of the blades. Said portions 12 are so arranged that they are juxtaposed in the 65 four blades a, b, c, d, of each group and appear as shown in Fig. 3.

The parts 12 of the blades a, b, c, d, of the groups have notches 13, the distance and position of which vary and serve a purpose 70 to be hereinafter explained. As all the blades are carried in the frames 8, they are all raised and lowered at the same time.

During one revolution of the main shaft 1 the blades are raised and lowered once. 75 Levers 15 which are parallel with the levers 4 and are pivotally connected to the machine frame by pins 16 are pivoted to the supporting arms 7, so as to maintain the latter vertical while they are raised and 80 lowered by the cam 2.

Mounted to rotate freely in the machine frame 5, are rollers 17 on which are carried four slides 18 adapted to be moved horizontally and provided with box shaped 85 ends 19.

Projecting from the sides of each slide 18 are pins 20^a, 20^b, 20^c, 20^d, 20^e, 20^f, 20^g, 20^h, 20ⁱ, 20^j. Said pins are adapted to be engaged by forks 21 formed on the ends of levers 22 90 which are pivoted to rocking arms 23.

All the arms 23 are fixed on a shaft 24 which is carried in the machine frame 5 and to which motion is imparted from a cam 25 by means of arms 37. The levers 22 are suspended by links 26 which are pivoted to extensions 27 of knife shaped lifters 28.

There are ten lifters to each slide 18, or one lifter for each pin, making a total of forty lifters. These lifters are pivoted on a 100 shaft 29 at one end while at their other ends they are suspended on springs 30 which tend to pull the lifters upwardly, that is to say to hold them against the blades 11.

When the blades are in such a position that the recesses 13 of one group of blades are registering, the lifter which is beneath these recesses can be raised into them which causes the fork 21, which is connected to that particular lifter, to engage one of the pins. 110

This, in a manner hereinafter explained, determines the distance through which the slides 18 move horizontally.

Fig. 5 shows diagrammatically one group 5 of blades in their fundamental position and in ten other positions. I indicates the fundamental position in which the recesses 13 of the blades are in such relative position that none of the lifters 28 can engage them, that 10 is to say none can enter four adjacent recesses. In the position II the blade *a* has been displaced so that the four recesses 13, at the bottom of the figure, are registering and the lowermost lifter 28 can enter them 15 and be raised somewhat so that the fork 21 connected to that lifter engages its pin of the corresponding slide 18. In the position III the blade *b* has been displaced which allows the next lifter to be raised. Moving the 20 third blade *c* into the position IV allows the third lifter to be raised; moving the blade *d* into the position V allows the fourth lifter to be raised. In position VI the blades *a* and *b* are displaced together allowing 25 the fifth lifter counting from the bottom to be raised, while displacing the blades *b* and *c*, position VII allows the fifth lifter from the top to be raised; displacing the blades *c* and *d*; position VIII allows the 30 fourth lifter from the top to be raised. Displacing the blades *a* and *c* together; position IX allows the third lifter from the top to be raised displacing the blades *b* and *d* together, position X allows the second lifter 35 from the top to be raised, and displacing the blades *a* and *d* together position XI allows the topmost lifter to be raised. The displacing of the several blades is effected from the card 31 which in a known manner, is 40 guided by a lever 32 that is rocked to and fro by means of a cam groove disk 33 fixed on the shaft 1. The blades are returned to their normal positions by means of a bar 34 which is operated from the shaft 1 by 45 means of a cam 36 and a rod and bell crank lever 35.

Each of the box-like frames 19 of the slides 18 are provided with racks 38 and 39. Supported in a bearing 40, Fig. 2, is a shaft 50 41 which is provided with a slide sleeve 42, having a pinion 43, thereon which is prevented from turning relatively to the shaft 41 by means of a groove and feather arrangement. The sleeve 42 is provided with a grooved collar 44, which is engaged by the fork shaped end 45 of a lever 47, which is pivoted on a rod 46. By means of rods 48 and 49, each lever 47 is connected to levers 50 and 51, respectively, which levers are pivoted on the rod 9 and are adapted to be moved by lateral extensions 14 of the blades *f* when the levers engage recesses in the said extensions, (see the levers 50 in Figs. 2 and 3). When the blades *f* are so displaced by 55 the card that the extensions 14 engage the

levers 50, then, when the blades are moved downward by means of the cams 2 through the parts 8, 7, 4, 3, the pinions 43 are raised from the position shown in dotted lines in Fig. 2, and caused to engage the racks 38. When the levers 51 are engaged and moved downward by the extensions 14, the pinions 43 are caused to engage the racks 39. It follows that the shafts 41 are turned either forward or backward under the control of the 75 levers 50 and 51.

Mounted to rotate freely on the shafts 41, of the slides on each side of the machine, (Figs. 2 and 4) are toothed wheels 52 which are connected with the bevel wheels 53 of a differential gear 54. This gear actuates toothed wheels 55 which are engaged by toothed wheels 56, 57. The wheel 56 through suitable gear causes the horizontal movement of the frame and the wheel 57 80 through suitable gear causes the vertical movement of the frame. It is necessary to correct the movement, either by addition or subtraction. This is done by the slides disposed between the two end slides referred to. 90 The shafts 41 of the intermediate slides have pinions 58 which mesh with the wheels 52, as seen in Fig. 3. The pins 20^a to 20^c in these slides are also displaced laterally with relation to each other, but the effect of the lateral distance between two pins is, by the ratio of the wheels 52 and 58, reduced to one tenth of the lateral distance between corresponding pins on the two end slides 18. By this arrangement it is possible to increase or 95 diminish the stroke, say two millimeters, and thus correct it, by moving the two inside slides.

60 designates a rail which is adapted to be oscillated in the direction of the arrow 105 (Fig. 2). This rail keeps the lifters 28 down when the blades 11 move upwardly; said rail being actuated from a cam 62 on the shaft 1 through links 61.

I claim.

1. In a jacquard mechanism for embroidery machines, the combination with a plurality of jacquard card controlled notched blades arranged in groups, of a plurality of lifters arranged transversely of each group of blades, said lifters controlling the extent of movement of the embroidery frame of the machine, all the notches of a group of blades being normally out of alignment, and when one or more of said blades 115 of a group are selected there will be only one set of aligned notches, whereby only one of the lifters pertaining to the group can be actuated.

2. In a jacquard mechanism for embroidery frames, the combination with a plurality of jacquard controlled blades arranged in groups; of a plurality of transversely arranged lifters pertaining to each group of blades, each group of blades be- 125 130

110

- ing inoperative to all its lifters until one or more of the blades has or have been controlled, and then operative with respect to only one lifter.
5. 3. In a jacquard apparatus for embroidery machines, a plurality of blades combined in groups, each of the blades provided with a plurality of notches, frames movable in vertical direction and connected to each other supporting the ends of said blades, a jacquard card for separately displacing the blades so that according to the displacement of one or several blades of a group different notches become located side by side, and 15 knife shaped controlling means provided for each of said groups arranged transversely to said blades and adapted to enter in the notches located side by side, substantially as described.
- 20 4. In a jacquard apparatus for embroidery machines, a plurality of blades combined in groups, each blade having notches, vertically movable frames connected to each other supporting the ends of said blades, a jacquard card for separately displacing the blades, so that according to the displacement of one or several blades of a group different notches become located side by side, knife shaped lifters provided for each of said groups arranged transversely to said blades and 25 adapted to enter in the notches located side by side, a pantograph, means controlling the pantograph comprising slides, pins carried by said slides and fork shaped levers connected to said lifters and adapted to engage said pins, substantially as described.
- 25 5. In a jacquard apparatus for embroidery machines, a plurality of blades combined in groups, each blade having notches, vertically movable frames connected to each other supporting the ends of said blades, a jacquard card for separately displacing the blades, so that according to the displacement of one or several blades of a group different notches become located side by side, and 30 knife shaped lifters provided for each of said groups arranged transversely to said blades and adapted to enter in the notches located side by side, substantially as described.
- 35 6. In a jacquard apparatus for embroidery machines, a plurality of blades combined in groups, each blade provided with several notches, vertically movable frames connected to each other, supporting the ends of said blades, a jacquard card for separately displacing the blades, so that according to the displacement of one or several blades of a group different notches become located side by side, knife shaped lifters pro- 40 vided for each of said groups arranged transversely to said blades and adapted to enter in the notches located side by side, and a pantograph controlled by said lifters, substantially as described.
- 45 6. In a jacquard apparatus for embroidery machines, a plurality of blades combined in groups, each blade being provided with several notches, vertically movable frames connected to each other supporting the ends of said blades, a jacquard card for separately displacing the blades, so that according to the displacement of one or several blades of a group different notches become located side by side, knife shaped lifters provided for each of said groups arranged transversely to said blades and 50 adapted to enter in the notches located side by side, a pantograph, means controlling the pantograph comprising slides, pins carried by said slides and fork shaped levers connected to said lifters and adapted to engage said pins, substantially as described.
- 55 7. In a jacquard mechanism for embroidery machines, the combination with a plurality of jacquard card controlled notched blades arranged in groups, and vertically movable frames common to all of the blades; of a plurality of lifters arranged transversely of each group, and means to move the blades against the lifters, each group of blades being inoperative to all 60 its lifters until one or more of the blades have been operated and then operative with respect to only one lifter.
- 70 In testimony that I claim the foregoing as my invention, I have signed my name in 65 presence of two subscribing witnesses.

VICTOR KOBLER.
